(57) **CLAIM**

The present design is a design for a reflector for illuminator.

DESCRIPTION

FIG. 1 is a perspective view of the reflector for illuminator showing a new design;

FIG. 2 is a front view thereof;

FIG. 3 is a rear view thereof;

FIG. 4 is a left-side view thereof;

FIG. 5 is a right-side view thereof;

FIG. 6 is a reduced top plan view thereof;

FIG. 7 is a reduced bottom view thereof;

FIG. 8 is a further reduced perspective view showing the reflector for illuminator in use;

FIG. 9 is an enlarged and partial perspective view thereof;

FIG. 10 is an enlarged and partial front view thereof;

FIG. 11 is an enlarged and partial top plan view thereof; and,

FIG. 12 is a reduced perspective view thereof.

The broken lines showing environmental structures in the drawings form no part of the claimed design.
